METHOD AND APPARATUS FOR OPENING ENVELOPES

Willard T. Kennel, Kalispell, Mont.

Application September 13, 1954, Serial No. 455,537

1 Claim. (Cl. 164—66)

The present invention is a method of and apparatus for opening envelopes.

One object of the invention lies in the provision of a method of opening envelopes which eliminates the possibility of tearing or cutting the contents thereof.

Another object of the invention lies in the provision of a method of and apparatus for opening envelopes which enables one to open envelopes by the use of one hand only.

Another object of the invention lies in the provision of a letter opener which is automatically actuatable, thus providing trouble free means for opening envelopes.

Other objects of the invention are to provide a letter opener of the character described which will be comparatively simple in construction, strong, durable, highly efficient and reliable in use, compact, and which may be manufactured at low cost.

All of the foregoing and other objects of the invention will become apparent from a study of the following specification taken in connection with the accompanying drawings wherein like characters of reference designate corresponding parts throughout the several views and wherein a preferred form of the invention is shown.

It should be understood however that the drawings and description are illustrative only and are not intended to limit the invention except insofar as it is limited by the claim.

In the drawings,

Figure 1 is a perspective view of the base of a lamp within which the letter opener constituting the subject matter of this invention is disposed;

Figure 2 is a transverse vertical cross section as at line 2—2 of Figure 1; and,

Figure 3 is a fragmentary skeletal perspective view of the cooperating shearing and actuating elements of the letter opener.

Referring now more particularly to the drawings, the disclosed embodiment of the invention comprises a frame indicated in general by the numeral 10 which includes a decorative housing 11 having front, side, back and top walls 12, 13, 14 and 15 adapted to cover a removable body portion 16 having a bottom wall 17 and an upwardly spaced horizontal intermediate partition 18 supported on vertical side panels 19 carried by the bottom wall 17.

In the disclosed embodiment of the invention we show a pair of vertical standards 50 which are adapted to support a lamp (not shown) and are internally threaded at their lower ends at 51 to receive a headed bolt 52 which is adapted to releasably secure the body portion 16 within the housing 11.

A conventional electric motor 20 is supported on a side panel 19 and has its driving shaft 21 connected to a suitable speed reduction motion transmission indicated in general by the numeral 22. The reduction transmission is here shown to be a worm and gear combination but it will be understood that any one of many conventional transmissions may be employed. An additional motion transmitting device such as a belt or chain 23 transmits

2

the rotary motion from the transmission 22 to the rotatable element 24.

Rotatable element 24 is journaled at its ends on opposed side panels 19 and is provided with a cylindrical peripheral face 25 which is disposed spaced from a shear bar 26. The face of the element 24 may be spaced from the cutting edge 27 of the shear bar 26 any desired distance, however, for the most practical application of the invention it is desired that this spacing be substantially equal to the paper thickness forming the body of an envelope to be opened thereby. It is necessary that this spacing be at least equal to this thickness to insure opening of the envelope and is preferable that the spacing be greater than the paper thickness of the envelope body but not so great as to be liable to permit sufficient overhang of the envelope to include a portion of its contents which may extend beyond the cutting edge 27 of the shear bar 26.

A shearing blade 28 is spirally arranged on the peripheral face 25 of the rotatable element 24 and extends the full length of the element 24 and substantially 270 degrees of its circumference leaving substantially 90 degrees of its circumference clear to form a stop against which the edge of an envelope placed with its marginal edge portion extending over the shear bar 26 may strike to limit the overhang thereof. Obviously the depth of the blade 28 is substantially the same as the spacing between the face 25 and the shearing edge 27 of shear bar 26 so that when the element 24 is rotated the shearing blade 28 cooperates with the shear bar 26 to shear off the marginal edge portion of an envelope extending beyond the shear bar 26.

A supporting plate 29 is carried by front panel 19 and extends at right angles to the shear bar 26 forming a smooth surface upon which the envelope to be opened may be slid into position on the shear bar 26. The housing 11 is provided in its front wall 12 with an elongated slot or opening 30 through which an envelope may be inserted into the letter opening mechanism and the slot 30 opens onto the upper surface of the plate 29 to properly guide movement of the envelope to an opening position on the shear bar 26 with its forward edge impinging against the peripheral face 25 of the element 24. It is then only necessary to rotate element 24 one revolution whereupon the edge of the envelope is sheared off, opening the envelope.

To provide means for energizing the prime mover 20 I provide an energizer or actuating mechanism 31 which is seen to consist of a vertically tiltable table 32 journaled at 33 on a vertically disposed plate 34 and the table supports a mercury or other type normally open electric switch 35 which forms a part of the electric circuit including the prime mover or electric motor 20. As viewed in Figure 2 the switch 35 is disposed in its normally open position and upon insertion of an envelope through the slot 30 the pressure of the envelope depresses a depressible resilient element 36 which is operably connected at 37 to the tiltable table 32. To eliminate the possibility of the resilient element 36 lifting the envelope as it is inserted through the slot 30 I provide one or more resilient fingers 38 carried by the housing 11 and yieldably resting upon the plate 29 thereby maintaining the envelope flat upon the plate 29 and insuring its proper positioning against the peripheral face 25 of the element 24. When the envelope is inserted it depresses element 36 which actuates switch 35 energizing motor 20 which through the transmission elements 22 and 23 rotates the rotatable element 24 and shears the edge from an envelope bearing against the peripheral face 25. As long as the envelope is disposed in a position to depress the element 36 the motor continues to operate and the element 24 continues to rotate. However, when the envelope is removed the switch 35 is raised by means of the

resilient element 36 and connection to the motor 20 is broken.

To permit proper positioning of an envelope to be opened it is necessary that the rotatable element 24 be stopped in a position wherein the shearing blade 28 is disposed away from the shear bar 26 thus presenting an unobstructed area of the peripheral face 25 toward the shear bar 26.

Since it is necessary that the rotatable element 24 always stop in a position with the shearing blade 28 disposed away from the shear bar 26 I have provided at one end on the element 24 a cam 39 which is adapted to actuate a cam follower 40 carried by a rotatable rod 41 having a bell crank lever 42 at its opposed end. When the rotatable element 24 is disposed in proper position the cut away portion 39' of cam 39 releases the cam follower 40 which permits counter rotation of rod 41 and simultaneous release of the rockable table 32 thus automatically opening switch 35. However, when the shearing blade 28 is disposed in shearing relation to the shear bar 26 the cam 39 depresses follower 40 rotating rod 41 causing the bell crank lever 42 to tilt the plate 32 thus actuating switch 35 energizing motor 20 until such time as the follower 40 is released by the cut away portion 39' whereupon the motor stops with the rotatable element 24 in proper position to receive a subsequent envelope.

Having thus described my invention, I claim:

An envelope opener comprising a supporting frame having an access opening through which an envelope may be inserted into the frame; said access opening extending substantially the full width of said frame; a fixed shear bar coincident in length to said access opening carried by the frame and disposed to support a marginal edge portion of an envelope inserted into the frame through said access opening; a unidirectional rotatable element coincidental in length to said shear bar and having an annular

peripheral face disposed spaced from said shear bar and constituting a stop against which the edge of said envelope strikes to limit the amount of marginal edge portion extending over the shear bar; a shearing blade spirally carried by said element and extending substantially the full length of said shear bar and terminating short of traversing the full circumference of said element and disposed to cooperate with said shear bar upon rotation of said element for shearing said marginal edge portion from said envelope; an electric motor operably connected for rotating said element; an electric circuit connected with said element and including a normally open switch; weight depressible means for actuating said switch and operable upon insertion of an envelope through said access opening; cam means associated with said rotating element for actuating said switch when said shearing blade is disposed in cooperating relation to said shear bar and adapted to release said switch when said shearing blade departs from said shear bar whereby to stop rotation of said rotatable element with said shearing blade removed from said shear bar.
